UNITED STATES PATENT OFFICE.

JOHN A. HUSSEY, OF DE KALB, ILLINOIS.

PIANISSIMO DEVICE FOR GRAND PIANOS.

1,392,331.

Specification of Letters Patent.

Patented Oct. 4, 1921.

Application filed September 27, 1919. Serial No. 328,046.

To all whom it may concern:

Be it known that I, JOHN A. HUSSEY, a citizen of the United States, residing at De Kalb, in the county of De Kalb and State 5 of Illinois, have invented a new and useful Pianissimo Device for Grand Pianos, of which the following is a specification.

My invention relates to pianissimo devices for grand pianos, *i. e.*, pianos in which the 10 strings lie in a horizontal plane and the hammer strokes are substantially vertical, and the objects of my improvements are first, to reduce the hammer stroke without changing the position of the key; second, to so construct the pianissimo mechanism that it can 15 easily be applied to any standard make of action; third, to provide a device of the type described in which a normally inclined thrust rod is arranged for movement into 20 upright position between a key and an action support to move the latter toward the strings, and fourth, to make a simple, cheap and durable device.

Other objects and advantages will appear 25 in the following specification, and the novel features of the invention will be particularly pointed out in the appended claims.

This invention is an improvement on my invention forming the subject matter of 30 Patent No. 1,289,449, issued December 31, 1918. In the invention covered by said patent, the rock shaft which operates the pianissimo device is located in front of the action mechanism, and in this present invention the said 35 rock shaft is located below the action and above the key just in front of the capstan screw.

To describe my invention so that others versed in the art to which it pertains can 40 make and use the same, I have illustrated it on the accompanying two sheets of drawings forming a part of this specification and in which:

Figure 1, is a side elevation of a grand 45 piano action embodying my invention and showing the parts in normal position for ordinary playing; Fig. 2, is a similar view showing the pianissimo device brought into action; Fig. 3, is a vertical sectional view 50 of the action shown in the normal position as in Fig. 1; Fig. 4, is a similar view showing the parts in the position which they assume

when the pianissimo device is brought into action as in Fig. 2, and Fig. 5, is a similar view showing a modified form of my invention. 55

Similar reference characters refer to similar parts throughout the several views.

While I have illustrated and will describe my invention in connection with a grand 60 piano action, it will be understood that it can be applied to any other style of piano action.

The ordinary key frame 6 is shown having the balance rail 7 on which are mounted the 65 keys 8 in the usual manner. The keys 8 are provided with capstan screws 9 and back checks 10 as usual.

An action rail 11 supports the pivoted 70 ends of the action supports 12 and the rail 13 supports the flanges 14 to which the hammer shanks 15 are pivoted. The hammer rest rail 16 is located as usual in a position to have the hammer shanks contact with the cushioned upper side thereof. The jacks 17 75 are pivoted at 18 to the free ends of the action supports 12, and the repetition levers 19, are pivotally mounted on the middle portions of the action supports in the usual way. The mechanism thus far described comprises 80 an ordinary grand piano action and forms no part of my invention.

It is customary in pianos to have a pianissimo or soft pedal and when this pedal is 85 depressed with the foot it acts through certain connections and raises the hammer rest rail 16 a sufficient distance to lift all the hammers and support them in a position much closer to the strings 20 than they normally are. This lifting of the hammers results in releasing the usual downward pressure on the capstan screws 9 and permits the front exposed ends of the keys to drop in proportion to the raising of the hammers. This lowering of the keys on the keyboard 90 of the instrument interferes with the proper production of music. With the use of my invention the hammers are lifted and retained in a raised position close to the strings 20 without in the least disturbing the position of the keys out of the normal. Thus there is no interference with the proper production of music in a piano embodying my 100 invention.

My invention comprises a lost motion device which is interposed between the action support and the rear end of the key near the capstan screw and consists of a thrust rod 21 which has its upper end pivotally connected by a link 22 to a flange on the block 23, and has its lower end pivotally connected by a link 24 to a flange secured on a rock shaft 25. When the rock shaft 25 is in the position shown in Figs. 1 and 3, the post 21 is not erect and is out of contact with both the action support 12 and the key 8; and when the rock shaft 25 is in the position shown in Figs. 2 and 4, the post 21 is erect and is in contact with both the action support 12 and the key 8 and is so adjusted in length that the key will be held in its normal position when the hammer is raised to be close to the string 20. The rock shaft 25 is moved from its normal position as shown in Figs. 1 and 3, to its operated position as shown in Figs. 2 and 4 by depressing the pianissimo or soft pedal. The depressing of the soft pedal, 25 not shown, moves an operating rod 26 upwardly and this rod in turn lifts the hammer rest rail 16 which of course lifts the hammers. Depending from the hammer rest rail 16, preferably at each end of the action, 30 is an arm 27 rigidly secured to the hammer rail. Each arm 27 is connected adjacent its upper end by a link 28 to the action frame 29, and has its lower end pivotally connected to one end of a curved lever 30 that 35 is intermediately pivoted to the action frame 29 and is in effect a bell crank. The other end of each lever 30 is connected by a short link 31 to the free end of a rocker arm 32 rigidly secured to the rock shaft 25. 40 The parts are so arranged and constructed that when the soft pedal is in its normal, raised position, the hammers are all in normal position and the rock shaft 25 is in normal position; *i. e.*, in such position that 45 the thrust rod 21 is tilted and out of contact with both the action support 12 and the key 8; and when the soft pedal is depressed, the hammers are all in a raised position close to the strings 20 and the rock shaft 25 is in an 50 operated position; *i. e.*, in such position that the thrust rod 21 is erect and in contact with both the action support 12 and the key 8, thus holding the key in a normal position, although the hammer is in a raised position. 55 Suitable springs 33 are provided to normally depress the hammer rest rail 16 and other suitable springs 34 are provided to normally yieldingly depress the upper ends of the thrust rods 21 to insure non-interference with the action supports 12. Cushions and adjustments are provided wherever necessary as is customary in piano actions.

It will be noted that the parts embodying my invention can readily be applied to

a standard make of piano action and that the same when so applied are within the confines of the action itself, so that there is no interference with any part of the piano case within which the usual piano action is placed.

In Fig. 5, I have illustrated a modified form of my invention which may be preferred in some construction of pianos, and which consists in omitting the raising of the hammer rest rail 35, which in this case is shown to be rigidly secured to the action frame 29. The rock shaft 25 is operated directly from the pedal rod 36, the upper end of which contacts with the free end of the rocker arm 37 rigidly secured to the rock shaft 25. A suitable spring 38 is provided to depress the free end of the crank arm 37 and the rod 36.

Having thus fully described my invention what I claim as new and desire to secure by Letters Patent of the United States is:—

1. In combination with the keys and hammer action of a grand piano, said hammer action including a rest rail, an action frame, and an action support, a pianissimo device comprising an operating rod for raising the hammer rest rail, a depending arm carried by the rest rail, a rock shaft journaled in the action frame, a rocker arm carried by said rock shaft, a thrust rod for each key, means for movably supporting the thrust rod between the key and the support normally out of contact with both and for connecting the thrust rod with the rock shaft, and a lever and link device connecting the rocker arm and the said depending arm, whereby the rock shaft is operated whenever the hammer rest rail is raised, so that the thrust rod is moved into vertical position between the key and its action support to support the latter.

2. In combination with the keys and hammer action of a grand piano, said hammer action including a rest rail, an action frame, and an action support, a pianissimo device comprising thrust rods movably supported between the respective keys and the corresponding supports and normally out of contact with both supports and keys, and means arranged between the rest rail and the said thrust rods for moving said thrust rods into contact with the keys and the supports for supporting the latter in adjusted positions.

3. In combination with the keys and hammer action of a grand piano, said hammer action including a rest rail, an action frame, and an action support, a pianissimo device comprising a thrust rod for each key, a transverse rock shaft journaled in the action frame and located to the rear of the front line of said frame, means for movably supporting each thrust rod between a key and the corresponding support and out of contact with both, a rocker arm rigidly

connected with said rock shaft, and means for operating the rocker arm to occasion the movement of said thrust rods into contact with both keys and the corresponding supports.

In testimony whereof I have signed my name to this specification in presence of two

subscribing witnesses, this 31st day of July, 1919, at De Kalb, Illinois.

JOHN A. HUSSEY.
